(57) **CLAIM**

The ornamental design for a night light, as shown and
described.

DESCRIPTION

FIG. 1 is a front side elevational view of a night light;

FIG. 2 is a rear side elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a perspective view thereof.

The broken lines shown on the drawings are for illustrative
purposes only and form no part of the claimed design.
